UNITED STATES PATENT OFFICE.

EDWARD Y. WHITE, OF SAN ANTONIO, TEXAS.

FRAME FOR MOTOR-BICYCLES.

1,075,886.

Specification of Letters Patent. Patented Oct. 14, 1913.

Application filed March 9, 1906. Serial No. 305,152.

To all whom it may concern:

Be it known that I, EDWARD Y. WHITE, citizen of the United States, residing at San Antonio, in the county of Bexar and State 5 of Texas, have invented certain new and useful Improvements in Frames for Motor-Bicycles, of which the following is a specification, reference being had therein to the accompanying drawing.

10 This invention relates to spring frames for motor bicycles.

The object of the invention is to produce a frame in which the motor engine may be conveniently and compactly located, and 15 which frame shall be strong and stiff enough for usage on ordinary roads, and sufficiently yielding to afford a comfortable seat, and to prevent breakage under ordinary conditions of usage.

20 The invention involves in its construction a combination of mechanical elements forming a cushion for the motor and accessories, as hereinafter described and claimed.

Figure 1 is a side elevation of so much of 25 a bicycle as is necessary to show the invention in a general way. Fig. 2 is a top plan view of top tube and connections. Fig. 3 is an elevation of the rear fork, and spring head thereof. Fig. 4 is a broken cross section of the front end of straps and hinge 30 hereinafter referred to, showing part of tube 16. Fig. 5 is an enlarged detail elevation of the straps and hinge whereby the sections of frame are jointed. Fig. 6 is a plan and Fig. 7 is an elevation of the lower 35 rear frame member. Fig. 8 is a side elevation of the lower tube (front) of the frame. Fig. 9 is a bottom view of the lower front tube of frame. Fig. 10 is a broken cross section of rear end of hinge and seat post tube. Fig. 11 is a vertical central section of the 40 spring head of the rear fork. Fig. 12 is an elevation of the slotted tube of the spring fork head. Fig. 13 is a vertical section of the cup piece of spring head. Fig. 14 is a bottom plan of the cap 39' forming the upper 45 end of slotted tube 38. Fig. 15 is a top plan of the lower spring tube, and Fig. 16 is a broken vertical section of the lower spring tube.

The engine or motor 1, of usual form, rests in a cradle, which cradle is composed of curved straps 3, one strap at each side of

the engine casing, and both connected to a head 4, which head has a socket or pintle for 55 connection with the seat post 5, said seat post being of usual construction. The straps 3 may be secured to the engine casing by screws or bolts 6. The seat post 5 is rigid with the top bar 7 of the frame, which bar is 60 hinged to a sleeve 8 rigid with the steering head 9, through which head 9 the front fork 90 passes. Bar 7 has an inclined arm 12, which arm has means of attachment to the head of the motor, as by means of screw 13. 65 The bars of the frame are generally tubes, as is usual. The engine, the straps 3, and post 5, the top bar 7, and the arm 12 connected to the engine, thus form a triangle, which in itself is rigid. The attachment of 70 the straps 3 to the engine permits some latitude in the style of engine which may be attached to the frame.

The front fork 90 passes through sleeve 9 and turns therein, as is common. Sleeve 9 75 has a rigid collar 15, and to this the lower front bar 16 is hinged. This bar 16 curves below the engine, and has a cross head 29, which is hinged to the head 4 at 32 just in rear of the engine or motor cradle. (See 80 Figs. 1 and 5.)

The lower rear bars 17, 17 of the frame are oval in form and tapering. Both these bars are rigidly connected to a cross T 18, which T is hinged between the straps 3 at 85 the front of the engine casing. The bars 17 thus straddle the frame bar 16, under the engine. Bars 17 are rigidly connected to socket 20, which socket 20 forms a bearing for the usual pedal shaft. The socket 20 is 90 also rigid with the lower side bars 22 of the rear part of the frame. Bars 22 are rigid with the rear axle bearing 23. The rear fork 24 is pivoted or hinged to the rear axle bearing at 30. A tube 25 is rigid with the 95 rear fork, and serves as a receptacle for the lower spring 33. Tube 25 has curved slots 34 in its upper end 35, which end is otherwise closed. A cup 36, preferably secured by screw threads to the lower end of tube 25, 100 serves as a means for assembling the parts which form the spring head of the rear fork. A slotted tube 38, having one end closed as at 37, has its slotted end passed through the curved slots 34 of the tube 25. The slotted 105 end of the tube 38 is externally screw

threaded, as at 40. A coiled spring 41 is inclosed between the tube ends 35 and 37. The cup 44, internally screw threaded at 45, passes over the slotted end of tube 38, and engages with the screw thread thereof. A spring 47 is inclosed in this cup, above the end 35 of tube 25. Cup 44 telescopes over tube 25, and can close down over said tube when the three springs inclosed are compressed.

10 But cup 44 cannot be removed from the rear fork, except by unscrewing from tube 38, and tube 38 can only be removed from tube 25 by withdrawal from the lower end thereof. Cup 44 has a hinge member 46, which is pivoted to the seat post near the top end thereof, as at 47.

A weight on the seat post tends to compress the springs in the rear fork head. The frame members 5 and 16 turn slightly 20 at the point of their pivotal or hinge connection to the engine, and the wheel base of the machine elongates, when weighted. As the rear lower frame section is hinged or pivoted at 31, in front of the engine, and the 25 front lower frame bar is hinged or pivoted, at 32, in rear of the engine, both sections being connected to the saddle on which the engine rests, this elongation is permitted.

The engine stands in the frame in inclined 30 position, with its center of gravity about at the center of the frame, and there is space above the engine for the usual gasoline supply tank.

The pedal connection for driving the 35 bicycle, and other parts not herein described, for steering, supporting the seat, etc., may be of usual or approved construction.

What I claim is:

1. The combination with the main frame, 40 steering head and rear forks, of a front bar pivoted at the front to the head and at the rear to the main frame, and a rear bar connected to the rear fork and pivoted at its forward end to the main frame.

45 2. The combination with the main frame, steering head and rear forks, of a front bar pivoted at the front to the head and at the rear to the main frame, and a rear bar connected to the rear fork and pivoted at its forward end to the main frame forward of the pivotal point of said front bar.

3. The combination with the main frame 55 steering head and rear forks, of a front bar pivoted at the front to the head and at the rear to the main frame and a rear bar pivoted at the rear to the rear fork and at the front to the main frame.

4. The combination with the main frame 60 steering head and rear forks, of a front bar pivoted at the front to the head and at the rear to the main frame and a rear bar pivoted at the rear to the rear fork and at the front to the main frame forward of the pivotal point of said front bar.

5. In a frame for motor bicycles, a triangular frame section of which the seat post and motor form a part, and a rear frame section consisting of lower bars hinged near the front of the engine, extending to the rear and adapted to receive the rear axle, 65 and a yielding connection from said lower bars to the seat post.

6. In a frame for motor bicycles, the central frame section having a cradle for the motor, lower frame bars hinged to the front 75 of said cradle and extending to the rear axle, the steering head, and a lower frame bar pivotally connected to the steering head and extending past the hinge of the lower frame bars to a hinge at the rear of the 80 motor.

7. The combination, in a frame for motor bicycles, of a cradle consisting of side straps for connection to the engine, a rigid frame section of which said cradle is a member, a front lower frame bar connected to the rear of said cradle, and a rear lower frame bar connected to the front of said section, said bars extending past each other, and yielding connections from the extremes of said lower 90 bars to said rigid frame section.

8. In a motor bicycle frame, the combination of a central rigid triangular frame section, a steering head hinged to said rigid section, a front lower bar hinged to said head and to the rigid section, a rear lower bar hinged to the rigid section and having the rear wheel bearing, and a yielding extensible member connecting the rear wheel bearing to the upper part of the rigid frame. 100

9. The combination of a rigid frame carrying a motor and comprising a seat mounting, a steering head pivoted to said frame and a front bar pivoted to said frame and to the steering head.

10. The combination of a rigid frame carrying a motor and comprising a seat mounting, a steering head pivoted to said frame, and a front bar pivoted to said frame and to the steering head, a lower rear fork pivoted to said frame, and an upper rear fork connected to the lower fork and pivoted to said frame.

11. The combination of a rigid frame carrying a motor and comprising a seat mounting, a steering head pivoted to said frame, and a front bar pivoted to said frame and to the steering head, a lower rear fork, an upper rear fork pivoted to the lower fork near the wheel axle, a cushion interposed between the upper fork and said frame comprising a member pivoted to the frame, and a continuation of the lower fork pivoted to said frame.

12. The combination of a rigid frame carrying a motor and comprising a seat mounting, a steering head pivoted to said frame, and a front bar pivoted to said frame and

to the steering head, a lower rear fork carrying a crank-hanger, an upper rear fork pivoted to the lower fork near the wheel axle, a cushion interposed between the upper fork and said frame comprising a member pivoted to the frame, and a continuation of the lower fork pivoted to said frame.

In testimony whereof I affix my signature in presence of two witnesses.

EDWARD Y. WHITE.
